UNITED STATES PATENT OFFICE.

MILTON McWHORTER, OF PLAYAS, NEW MEXICO.

APPARATUS FOR COMPRESSING ELASTIC FLUIDS.

1,270,310.

Specification of Letters Patent. Patented June 25, 1918.

Application filed July 3, 1916, Serial No. 107,403. Renewed May 15, 1918. Serial No. 234,763.

To all whom it may concern:

Be it known that I, MILTON McWHORTER, a citizen of the United States, residing at Playas, in the county of Grant and State of New Mexico, have invented a new and useful Apparatus for Compressing Elastic Fluids, of which the following is a specification.

An object of this invention is the production of an efficient device and method for compressing elastic fluids so that said fluids may be used to furnish power or for any purpose whatsoever that elastic fluids are used.

Another object is to produce a device of this character of maximum simplicity of construction and operation.

Another object is to produce a device of this character in which the piston will act on some strokes in the capacity of a prime mover and will also act on other of its strokes to compress air.

Another object is to store some of the energy of the exhaust when the piston is functioning as a prime mover, and also to compress atmospheric air when the piston is not functioning as a prime mover.

Other objects and advantages will appear in the subjoined detail description.

The accompanying drawings illustrate the invention.

Figure 1 is a side elevation of an apparatus built in accordance with this invention for carrying out the newly invented method, the gear case being omitted for clearness of illustration.

Fig. 2 is an enlarged end view of the cylinder and exhaust valve operating gear.

Fig. 3 is a sectional detail of the piston and cylinder and its parts.

Fig. 4 is an enlarged elevation of the intake valve chamber, a portion being shown in section to expose the needle valve, fuel port and fuel control valve to view.

Fig. 5 is a sectional elevation on line indicated by x^5-x^5 , Fig. 4.

There is provided a cylinder 1 of any suitable construction and a piston 2 working in said cylinder and connected by a pitman 3 to a crank shaft 4 on which, if desired, may be mounted a fly wheel 5.

The cylinder 1 is provided with a port 6 controlled by a valve plug 7 having a valve stem 8 terminating in a head or abutment 9, there being a coil spring 10 between the abutment 9 and the outer end of a guide 11 for the valve stem so as to tend to hold the

valve plug 7 in closed position to close the port 6.

When relatively low pressures of explosive gases are to be dealt with in the cylinder 1, the single exhaust port 6 will be sufficient, but when high pressures are to be used, it is advisable to have an auxiliary exhaust port 12 opening from near the inner end of the cylinder 1, said port 12 being opened and closed by the piston 2 in a manner well understood in the art.

The exhaust port 6 communicates with a pipe line 13 which discharges into a receiver or tank 14, said pipe line being provided with an air inlet valve 15 and also with a check valve 16. The exhaust port 12 communicates with a branch 17 of the pipe line 13, though obviously said branch pipe 17 could discharge directly into the receiver 14 instead of by way of the pipe line 13. The branch pipe 17 is provided with a hand valve 18 and check valve 18'.

The receiver 14 may be provided with a suitable pressure gage 19 and with a blow off or safety valve 20. The receiver 14 is provided with a discharge pipe 21 having a valve 22, it being understood that the pipe 21 may be extended to the place where the compressed fluids are to be utilized.

The valve stem 8 is adapted to be engaged by one end of a lever 23 which is pivoted at 24 to a bracket 25 connected to the cylinder 1, the other end of said lever being provided with a roller 26 extending in the path of movement of a cam 27 on a cam shaft 28 that is connected by suitable gearing 29 to the shaft 4 as is well understood in the engine art to intermittently open the valve 7.

The cam shaft 28 also operates a governor indicated in general by the character 30, said governor being connected by a link 31 and arm 32 to an air control valve plate 33 having slots 34 adapted to register with slots 35 in the rear wall of a chamber 36 when the valve plate is moved for that purpose, the front wall of said chamber being provided with openings 37 to admit air therethrough. The governor 30 may be of any suitable type, the action thereof being well understood, and it suffices to state that when the centrifugally operated elements of the governor move outward they operate the link 31 to move the arm 32 in a direction to cause the valve plate 33 to close the air openings 35. When the openings 34, 35 reg-

ister with one another, the chamber 36 communicates therethrough with an inlet port 38 controlled by an inlet valve plug 39, the stem 40 of said valve plug being operated 5 to move the valve plug 39 into port opening position by a lever 41 fulcrumed on the pivot 24. The lever 41 is provided with a roller 42 adapted to be engaged by a cam 43 on the cam shaft 28 so as to intermittently 10 open the valve plug 39 against the pressure of the valve closing spring 44 in a manner well understood in the engine art.

The chamber 36 is provided with a fuel nozzle 45 connected by a fuel pipe 46 to a 15 suitable source of fuel supply, said nozzle 45 being controlled by a valve plug 47 normally held closed on its seat 48 by a coil spring 49 as in Fig. 4, suction produced by outward movement of the piston 2 in the 20 cylinder 1 being relied upon, when the valve plate 33 is in open position, to open the valve plug 47 against the pressure of the spring 49 to suck in fuel in a manner well understood in the gas engine art.

25 The ignition device is indicated in general by the character 50 and need not be described in detail, since any suitable igniting device will answer the purpose and the invention is not limited to the exact construction of said device.

In practice, assuming that a charge of combustible mixture has been drawn into the cylinder 1, compressed and fired in a manner well understood in the gas engine 35 art, it is clear that the exploded charge will exhaust through the ports 6 and 12 into the pipe line 13 and its branch 17 and thence into the receiver 14 so as to raise the pressure in said receiver. Other charges will be 40 introduced, compressed and fired in the same way until the governor 30 operates at sufficiently high speed to move the valve plate 34 into position to close the openings 35.

The next succeeding opening movement 45 of the intake valve plug 39 will not admit any charge to relieve the partial vacuum in the cylinder 1 and consequently, the atmospheric pressure on the valve plug 7 being greater than the combined pressures 50 of the spring 10 and fluid inside of the cylinder, said valve plug 39 will open. The succeeding outstroke of the piston 2 instead of being an idle stroke sucks atmospheric air through the inlet valve 15, pipe line 13 and port 6 into the cylinder 1. Then the piston operates on its in stroke to compress the atmospheric air thus sucked in and the increased pressure opens the check valve 16 so that compressed air discharges 60 therethrough into the receiver 14. The apparatus continues thus in operation to intermittently suck in charges of atmospheric air and compress said charges and discharge them into the receiver 14 until the speed 65 of the governor slackens sufficiently to open

the openings 35, whereupon the piston will again function as a prime mover as before until the governor acts to cut off the explosive mixture, whereupon the piston will function to deliver compressed air to the 70 receiver 14 as before.

From the foregoing it is clear that the piston 2 makes no idle strokes for, when it is not drawing in a combustible charge to fire, it is sucking in atmospheric air and, 75 when it is not scavenging the burnt gases, it is compressing the atmospheric air sucked in and discharging said air into the receiver 14.

It is understood that a certain percentage 80 of efficiency is lost in the exploding charges because of exhausting said charges against whatever pressure there is in the receiver 14, but this is more than offset by reason of the great percentage of efficiency obtained 85 owing to the utilizing of all of the strokes of the piston and also owing to the saving of the pressure of the exhausting exploded gases.

The foregoing will enable those skilled 90 in the art to which the invention appertains to make and use said invention, it being understood that the construction may be varied within the spirit and scope of the appended claims.

95 I claim:

1. In combination, a cylinder having exhaust and intake ports, a piston in said cylinder, valves for said ports respectively, means to supply a combustible mixture to 100 the intake port, speed-controlled means to shut off the supply of mixture to the intake port, means to ignite the mixture, a receiver, and a pipe line connecting the exhaust port to the receiver, said pipe line 105 being provided with a check valve and with an air inlet valve.

2. In combination, a cylinder having exhaust and intake ports, a piston in said cylinder, valves for said ports respectively, 110 means to supply a combustible mixture to the intake port, means to ignite the mixture, a receiver, speed-controlled means to shut off the supply of mixture to the intake port, and a pipe line connecting the exhaust port to the receiver, said pipe line being provided with a check valve and with an air inlet valve.

3. In combination, a receiver, a cylinder having an intake port and a main exhaust port and an auxiliary exhaust port, valves for the intake port and main exhaust port respectively, a piston in the cylinder adapted to open and close the auxiliary exhaust port, means to supply a combustible mixture to the intake port, speed-controlling means to shut-off the supply of mixture, means to ignite the mixture, a receiver, and a pipe line connecting the exhaust ports to the receiver, said pipe line being provided

between the main exhaust port and receiver with a check valve and an air inlet valve, and said pipe line being provided between the receiver and auxiliary exhaust port with

5 a second check valve.

4. In combination, a cylinder having intake and exhaust ports, a piston in the cylinder, a crank shaft operatively connected to the piston, a fly wheel on said crank 10 shaft, a valve plug for the exhaust port, a spring to normally hold said valve plug closed, a cam shaft operatively connected to the crank shaft, means operative by the cam shaft to move the valve plug to open 15 the exhaust port, ignition means for the cylinder, a governor operative by the cam shaft, a receiver, a pipe line connecting the exhaust port to the receiver, a check valve in said pipe line, an air inlet valve 20 in said pipe line, and means operative by

the governor to cause the exhaust valve plug to open on the suction stroke of the piston to suck in a charge of atmospheric air through the exhaust port.

5. In combination, a gas engine cylinder, 25 a receiver for compressed gas, a conduit connecting the gas engine cylinder and the receiver, a check valve in said conduit opening toward the receiver, an atmospheric air inlet valve in said conduit between the check 30 30 valve and the gas engine cylinder, and a speed-controlled cut-off for the motive fluid supply of the gas engine.

Signed at Los Angeles, California, this 24th day of June, 1916.
